UNITED STATES PATENT OFFICE.

GUSTAV KOMAREK, OF ST. LOUIS, MISSOURI, ASSIGNOR TO CHARLES L. GILBERT, OF ST. LOUIS, MISSOURI.

CAR-TRUCK SIDE FRAME.

1,010,773.

Specification of Letters Patent.

Patented Dec. 5, 1911.

Application filed August 21, 1911. Serial No. 645,144.

To all whom it may concern:

Be it known that I, GUSTAV KOMAREK, a citizen of the United States, residing at St. Louis, Missouri, have invented a certain new and useful Improvement in Car-Truck Side Frames, of which the following is a full, clear, and exact description, such as will enable others skilled in the art to which it appertains to make and use the same.

10 This invention relates to car truck side frames, and has for its object to provide a side frame of novel construction which is so designed that the journal boxes or the axles can be removed without taking down the 15 side frame or disconnecting it from the other parts of the truck.

Figure 1 of the drawings is a side elevational view of a car truck side frame constructed in accordance with my invention; 20 Fig. 2 is a top plan view of Fig. 1; Fig. 3 is an enlarged end view of the side frame; Fig. 4 is a vertical sectional view taken on the line 4—4 of Fig. 2; Fig. 5 is a perspective view of one of the removable pedestal 25 columns; and Fig. 6 is a perspective view of the tie-bar that connects the removable pedestal columns to the main portion of the side frame.

Referring to the drawings which illustrate 30 the preferred form of my invention, A designates a truck side frame provided with integral pedestal columns 1 and integral portions 2 which extend over the journal boxes B. Removable pedestal columns C 35 are detachably connected to the side frame, preferably by means of bolts or other suitable fastening devices 3 which pass through said removable pedestal columns and through the portions 2 of the side frame 40 which project over the journal boxes. The lower ends of the removable pedestal column C are also preferably connected to the main portion A of the side frame by means of tie-bars D, and suitable fastening devices 45 such, for example, as bolts 4 which pass through the lower ends of the removable pedestal columns C, through the tie-bars D, and through flanges 5 on the main portion of the side frame arranged adjacent the 50 lower ends of the integral columns 1.

The particular shape of the removable pedestal columns C is immaterial so far as my broad idea is concerned, and the particular shape of the main portion of the side frame is also immaterial as my invention

consists broadly in a truck side frame having integral pedestal columns and a removable pedestal column coöperating with each of the integral pedestal columns for confining the journal boxes in position, thereby enabling the journal boxes or the axles to be removed without taking down the side frame or disconnecting it from the other parts of the truck.

In the construction herein shown which 65 represents the preferred form of my invention, each of the removable pedestal columns C consists of a cast member of approximately channel-shape in cross section provided adjacent its upper end with a horizontal web in which openings 6 are formed to receive the fastening devices 3, and provided at its lower end with an opening 7 for receiving the bolt 4 which passes through the tie-bar D. The tie-bars D also preferably consist of castings of approximately the shape shown in Fig. 6 wherein it will be seen that each tie-bar is provided at one end with an integral channel-shaped part 8 which receives the removable pedestal column C with which it coöperates, and at its opposite end with an integral channel-shaped part 8^a which receives the depending flange 5 on the main part of the side frame that is arranged in alinement with the integral pedestal column with which the tie-bar coöperates. The channel-shaped parts on the tie-bars hold both columns of each pedestal in alinement and reduce the shearing strains on the fastening devices 4, and, 85 if desired, the parts 2 of the side frame to which the removable pedestal columns C are connected, can be provided with depending lugs 9 that bear against the upper ends of the removable pedestal columns C, as shown 90 in Fig. 1, and thus reduce the shearing strains on the fastening devices 3 which connect the upper ends of said removable pedestal columns to the portions 2 of the side frame. I prefer to provide the portions 2 100 of the side frame with integral spring seat members E which receive the springs that are arranged between the side frame and the journal boxes, as shown in Fig. 4.

Having thus described my invention, what 105 I claim as new and desire to secure by Letters Patent is:

A truck side frame provided with integral pedestal columns and integral horizontally disposed portions which project over the 110

journal boxes, inverted cup-shaped spring seats formed integral with said horizontally disposed portions, removable channel-shaped pedestal columns butting against the under sides of said horizontally disposed portions at points beyond said spring seats and connected to same by fastening devices which are arranged inside of said columns, tie-bars arranged between each removable pedestal 10 column and the integral pedestal column on the side frame with which it coöperates, substantially channel-shaped portions on the

ends of said tie-bars that embrace the parts with which the tie-bars coöperate, and long bolts passing through said tie-bars and through the members between which the tie-bars are arranged. ¹⁵

In testimony whereof I hereunto affix my signature in the presence of two witnesses.

GUSTAV KOMAREK.
